UNITED STATES PATENT OFFICE

ROBERT T. BRIZZOLARA, OF NEW DORP, NEW YORK

ICE CUBE FORMING DEVICE

Application filed July 15, 1929. Serial No. 378,192.

This invention relates to ice cube forming devices, and more particularly to improvements in that type of ice cube forming devices which embody grids or intersecting plates adapted, when placed on the block of ice, to sink or melt their way into the block of ice and produce thereby a series of small sections or cubes of ice for table use.

The primary object which the present invention has in view is to provide certain improvements in a grid structure of the kind referred to and in a manner as hereinafter set forth, whereby to guide the grid structure as the plates thereof enter into the block of ice.

It is within the province of the present invention to provide a construction of means whereby the grid structure in its entirety will be guided and positioned with respect to the block of ice operated upon and in a manner designed to avoid waste of the ice and to prevent diminution in the size of the resultant ice cubes.

A further object of the invention is to insure the production of ice cubes of uniform size, and to make provision for repeated applications of the grid structure to the same block of ice without unnecessary waste of ice and in a manner to secure uniform cubes of ice as well as to prevent defacement of the same.

More particularly, the object and purpose of the invention are to provide for the grid structure guiding and positioning means in the form of projections joined to the grid structure and adapted to penetrate the ice block in advance of the intersecting plates of the grid structure. According to an important feature of the improvements, certain of the projections are arranged in angular relation with respect to each other so as to prevent any skewing action of the grid structure relatively to the block of ice. A further feature of improvement in this regard is to so arrange the projections that they will leave, after the production of each series of ice cubes, projection receiving recesses in the body of the block of ice for the re-application of the grid structure to the block of

ice, either in the same position or in a reversed end for end position.

The improvements of the present invention are capable of utilization with advantageous results in connection with ice cube forming structures of any type having means adapted to penetrate the body of the block of ice, whether the structure depends for its operation solely upon pressure, such as by the weight of the structure itself, or whether the structure has combined therewith a heat producing agency for promoting the melting of the ice to form the ice cubes. In connection with ice cube forming structures embodying heating means, by means of which the parts melt their way rapidly into the body of the ice block, my improved guiding and positioning means are especially efficacious in avoiding waste of ice and in preventing diminution in the size of the resultant ice cubes.

With the above objects and others in view, the invention consists in the improved ice cube forming device and in the form, construction and relative arrangement of the parts, as will be hereinafter more fully described, illustrated in the accompanying drawings forming a material part of this application, and subsequently incorporated in the subjoined claims.

The invention will be best understood by referring to the accompanying drawings, in which I have illustrated one simple and practical embodiment of the device, and in which,—

Figure 1 represents an elevational view showing my improved ice cube forming device upon a block of ice;

Fig. 2 represents a perspective view of my improved device; and

Fig. 3 represents a sectional plan taken on the line 3—3 of Fig. 1.

With more particular reference to the accompanying drawings, wherein I have illustrated a preferred form of construction, the grid structure is represented as comprising a plurality of longitudinally extending metallic plates 10 and a series of transversely extending metallic plates 11 arranged in intersecting relation so as to produce a series

of chambers 12 in which the ice cubes are formed when the intersecting plates penetrate the body of the ice block. It is in place to state here that the metallic plates have the 5 characteristic of heating plates, inasmuch as they absorb heat from the air and transmit the absorbed heat to the ice, thereby facilitating penetration of the plates into the block of ice. The intersecting plates enter or sink 10 into the ice by pressure, which may consist of the weight of the structure, or of the weight of the structure combined with a weight superposed thereon, or by virtue of pressure combined with the agency of heat for promoting 15 melting of the ice to form the ice cubes. For a full understanding of the construction, utilization and modes of operation of grid structures of this type, reference may be had to Letters Patent of the United States, 20 Nos. 1,709,709 and 1,709,710, granted to me on April 16, 1929.

In carrying my invention into effect in its preferred form of construction, the grid structure is provided with guiding and positioning means whereby to be stabilized upon the block of ice so as to prevent any appreciable skewing action of the structure with respect to the block of ice, and to cause the intersecting plates to be guided straight into the block of ice during the penetrating operation.

As exemplified in the accompanying drawings, the positioning and guiding means are in the form of depending projections of 35 which, in the present instance, four are shown, two depending projections 13 and 14 being fixed to one end of the grid structure, while two depending projections 15 and 16 are fixed to the opposite end of the same. These depending 40 projections extend downwardly beyond the plane of symmetry of the respective penetrating longitudinal edges 10' and 11' of the intersecting plates 10 and 11. According to an important feature of my invention, the 45 members of each pair of depending projections are arranged in planes at right angles to each other; and by preference, the members of each pair in diagonally opposite relation lie in planes parallel to each other. Thus, 50 upon an inspection of Fig. 2, it will be seen that the members 14 and 15 come in planes which are parallel to each other and that the members 13 and 14 also come in planes parallel 55 to each other and intersecting the planes of the first named members. By this arrangement, when the grid structure is placed upon a block of ice as 17, the projections 13 and 14 will produce recesses 13' and 14' in the 60 block of ice, while the other members 15 and 16 will produce recesses 15' and 16' in the block of ice. By reason of the fact that the 65 projections are arranged in the angular relation described, turning or twisting of the grid structure to one side is positively prevented

after the projections have penetrated into the block of ice to form recesses therein.

At each end of the grid structure, the projections are located in open corners at the junction of the outermost transverse plate 11 with the outside longitudinally extending plate 10. In the use of the grid structure, the end portions 18 of the longitudinally extending plates 10 comprise wings which form drain grooves or channels for draining off the water resulting from the melting of the ice during the production of the ice cubes in the chambers 12. With the depending projections located in the manner described, that is to say, in the open corners defining the junction of the transverse plates with the longitudinally extending plates, the water resulting from the melting of the ice pursuant to the penetration of the projections is also drained off through the grooves or channels produced by the wing portions 18. In case the block of ice is of less longitudinal dimension than the grid structure, the pair of depending projections at one end of the structure will be clear of the block of ice while the other pair of depending projections will maintain the structure against any twisting or turning movement. Obviously, if desired, additional depending projections may be fixed to the outer faces of the outer plates 10 at points intermediate the positions of the pairs of projections herein illustrated.

By virtue of the fact that the depending projections produce recesses in the block of ice in advance of the edges of the intersecting plates, the recesses thus produced constitute positioning means for the re-application thereto of the depending projections when, after the production of a series of ice cubes and the chipping off of the same from the ice block, it is desired to produce a subsequent series of ice cubes from the same ice block. In this way, waste of the ice is prevented and the ice block is kept in condition for the production of subsequent series of ice cubes of uniform size.

From the foregoing description, taken in connection with the accompanying drawings, it will be manifest that I have disclosed an extremely simple and thoroughly satisfactory form of construction which embodies the features of advantage enumerated in the statement of invention; and while I have, in the present instance, shown and described a preferred embodiment thereof as reduced to practice, it is to be understood that the construction is susceptible of modification in various particulars without departing from the spirit and scope of my invention or sacrificing any of its advantages.

I claim:

1. An ice cube forming device, comprising outer and inner intersection plates forming chambers, said plates having edges terminating in a common plane, adapted to enter into

a block of ice to produce ice sections in the chambers, and projections on certain of the outer plates, extending below the common plane of the edges of the plates and adapted to enter into the block of ice in advance of the edges of the plates.

2. An ice cube forming device, comprising intersecting plates forming chambers, said plates having edges terminating in a common plane, adapted to enter into a block of ice to produce ice sections in the chambers, and projections on certain of said plates extending below the common plane of the edges of the plates and adapted to enter into the block of ice in advance of the plates, certain of said projections being disposed in planes at right angles to the planes of the other of the projections.

3. An ice cube forming device comprising a structure provided with parts forming chambers for entering into a block of ice to produce sections in the chambers, and guide means depending from the structure for engagement with the block of ice, to hold the structure in position and prevent skewing thereof relatively to the block of ice and thus cause proper entering of said parts into the block of ice, said guide means functioning independently of the engagement of the device with the ice.

4. An ice cube forming device comprising a structure provided with parts forming chambers for entering into a block of ice to produce sections in the chambers, and guide means on various chambers of said structure and extending therefrom, said guide means being arranged for engagement with the block of ice in advance of the position of said parts, to hold the structure in position whereby to prevent skewing thereof relatively to the block of ice and thus cause proper entering of said parts into the block of ice.

5. An ice cube forming device comprising a structure provided with parts forming chambers for entering into a block of ice to produce sections in the chambers, guide means depending from the structure and consisting of projections in spaced apart positions for maintaining engagement with the block of ice whereby to prevent skewing of the structure on the ice and proper entering of said parts into the ice is effected.

6. An ice cube forming device comprising a grid structure provided with plates forming chambers for entering into a block of ice to produce ice sections in the chambers, and a pair of projections at each end portion of said structure projecting beyond the plates for maintaining engagement with the block of ice and enter said block in advance of said plates, the members of each pair being arranged in planes at right angles to each other.

7. An ice cube forming device having in combination transversely and longitudinally intersecting plates forming chambers, said

plates having edges terminating in a common plane adapted to enter into a block of ice to produce ice sections in the chambers, and projections on certain of the outer plates depending below the common plane of the edges and disposed thereon in diagonally opposite parallel planes, whereby said projections enter the block of ice in advance of the edges of the plates to prevent skewing of the device when in contact with the surface of said ice block.

In testimony that I claim the foregoing as my invention, I have signed my name hereto.

ROBERT T. BRIZZOLARA.
